UNITED STATES PATENT OFFICE

ADOLPH A. VLCEK, OF CLEVELAND, OHIO, ASSIGNOR OF ONE-HALF TO ARTHUR H. VAN HORN, OF LAKWOOD, OHIO

MEASURING INSTRUMENT

Application filed January 24, 1931. Serial No. 510,977.

My invention is an improvement in compasses, dividers, or other geometrical instruments.

One of the objects of my invention is to construct a compass or divider in which the legs carrying the points may be maintained in planes parallel to each other and each in turn perpendicular to a third plane such as is represented by the top surface of a drafting board, regardless of the degree of separation of the points.

Another object of my invention is to afford a simple means for quickly adjusting the points of a compass or divider to any desirable radius whereby the points may be maintained in such adjusted position without the danger of accidentally loosening or varying the adjustment.

A further object of my invention is to construct a compass or divider of the above named character which is simple of construction, durable and inexpensive to manufacture.

Other objects and advantages of my invention will become more apparent from the following description of two embodiments thereof, reference being made to the accompanying drawing in which like reference characters are employed to designate like parts throughout the same.

In the drawing:—

Figure 1 is a top plan view of one embodiment of my invention.

Figure 2 is a front elevation of the same. Figure 3 is a section taken on line 3—3 of Figure 2, and shows several of the parts in elevation.

Figure 4 is a front elevation of the compass or divider shown in Figure 2 and illustrates the relative positions of the parts when the respective legs of the compass or divider are in closed position.

Figure 5 is a fragmentary front elevation of a second embodiment of my invention.

Figure 6 is a fragmentary side elevation of the upper portion of the device shown in Figure 5.

Figure 7 is a section taken on line 7—7 of Figure 5, showing some of the parts in elevation.

In Figures 1 to 4 inclusive I have illustrated one embodiment of my invention in which the head of the compass or divider is shown at 1. The legs 3 and 4 are pivotally connected to the head on opposite sides thereof by means of the screw pins 2. The upper ends of the legs are pivotally secured within the slotted portions 5 of the head and are freely movable therein about the pins 2. The legs 3 and 4 carry extensions in the form of 60 socket members 6 and 7 respectively which are pivotally connected to the lower ends of the respective legs 3 and 4. In the embodiment illustrated the member 6 is shown as removably receiving a pencil or other 65 scribing instrument of the usual type while the member 7 removably carries the center point 9.

I have provided means for maintaining the extensions 6 and 7 in substantially parallel 70 planes throughout the entire adjustment of the legs 3 and 4. One form of this means is illustrated in Figures 1 to 4 inclusive as comprising a plurality of links 10 and 11 which are pivotally connected at their respective 75 upper ends to the head 1 by means of the screw pins 12, and at their lower respective ends to the respective extensions 6 and 7 by means of the pins 13. It will be noted in this embodiment of my invention that I have 80 provided the links 10 and 11 in pairs. This is more clearly illustrated in Figure 1 in which the links of each pair extend in planes on opposite sides of the planes of the respective legs 3 and 4. In this manner the construction 85 of the device is rendered sturdy and durable and assists in bracing the respective legs 3 and 4 against lateral movement with respect to the head of the device. I have also provided means for adjusting the legs 3 and 4 to any desirable position within the limits of adjustment, and to maintain the selected adjustment in fixed position. This means includes a shaft 14 extending into the head and downwardly between the respective adjustable 95 legs 3 and 4. The lower end of the shaft is threaded while graduations 14' may be applied above the threaded portion. A carriage 15 is slidable on the shaft and is provided with an opening 16 for receiving the adjust- 100

ing nut 17, the adjusting nut being threaded internally to receive the threaded portion of the shaft 14. The upper edge of the carriage may be used in conjunction with the graduations 14' to select an adjustment of the device or the adjustment may be read against the wall of the detent 60. Links 18 and 19 and 18' and 19' are pivotally connected to the carriage 15 as at 20 and to the legs 3 and 4 as at 21 and 22 respectively. It will be noted that these links operate on both sides of the respective legs 3 and 4 and between the respective links of the pairs 10 and 11. It will thus be seen that by turning the nut 17 in the proper direction on the shaft 14 that the carriage may be moved axially along the shaft in either direction to effect the desired adjustment of the legs and the desired spacing of the members 6 and 7 in substantially parallel planes.

A lock nut 23 is carried on the lower end of the threaded shaft 14 and may be brought into engagement with the carriage 17 after the latter has been adjusted on the shaft to the desired position, to lock the same against accidental displacement and to maintain the desired spaced adjustment of the members 6 and 7. The shaft 14 may be removably carried in the head 1 by means of a set screw 25. A knob or handle 24 may be integrally formed with the head 1 or may be fixedly inserted thereinto.

It will be seen that the apparatus shown as illustrating this embodiment of my invention is capable of quick adjustment and to subsequent finer adjustment. This is accomplished by loosening the set screw 25 and causing the shaft 14 to be moved axially in either direction therethrough to obtain a rough adjustment whereupon the set screw 25 may be screwed against the shaft and the nut 17 operated to obtain a finer adjustment between the members 8 and 9. This latter fine adjustment may be maintained by advancing the lock nut 23 into tight engagement with the bottom wall of the carriage 15 as illustrated in Figure 2.

In Figures 5, 6 and 7 I have illustrated another embodiment of my invention which in many respects is similar to that already described.

In this embodiment of the invention the head 26 is adapted to receive a shaft 27 threaded for a portion of its length, and is provided with an opening 28 for rotatably receiving a nut 29 removably secured to the shaft 27 by means of a set screw 30. The upper end of the shaft may extend beyond the head 26 to receive an operating knob or handle 31. In this embodiment of my invention the carriage is illustrated at 32 and is internally threaded to engage the threads of the shaft 27 for movement axially along the shaft when the shaft is rotated. Links 33 and 34 are pivotally connected at their re-

spective ends to the carriage 32 and to the connecting links 35 and 36 respectively, the links 35 and 36 being pivotally connected to the head 26 and to the leg extensions 37 and 38. It will be noted in this form of the invention that the links 33 and 34 are directly and pivotally connected with the links as distinguished from the form shown in Figures 1 to 4 inclusive in which these links are connected to the legs 3 and 4.

It will be seen therefore that by turning the nut 29 which is carried on the shaft 27, the internally threaded carriage 32 may be moved axially along the threaded shaft 27 in either direction to adjust the extensions 37 and 38 in any desired spaced parallel relation. When the adjustment is made it may be locked or maintained by tightening the nut 39 which extends through the head 26 and engages the shaft 27.

In use the form shown in Figs. 1 to 4 inclusive operates as follows: Assuming that the parts are in the positions shown in Figure 4, in closed position, and that it is desired to space the extensions 6 and 7 to a position illustrated in Figure 2, a quick adjustment may be made by loosening the nut 25 and slipping the shaft 14 upwardly through the head 1 and the handle or knob 24 until the approximate desired adjustment is obtained as indicated by the cooperating graduation marks and the upper wall of the carriage 15. Then the nut 25 is tightened on the shaft to prevent further movement of the shaft in either direction with respect to the head. It may be desired to obtain a finer adjustment by loosening the nut 23 on the shaft and then by turning the nut 17 in either direction until the points 8 and 9 are spaced accurately as desired. Then the nut 23 may be brought into tight engagement with the bottom wall of the carriage 15 to maintain this fine adjustment. The use of the device may then be carried out in the usual manner by gripping the knob 24. In the event that it is desired to disassemble the device as illustrated in these figures the nut 25 may be loosened together with either of the screw pins 20 and 21 and 22 to disconnect the links 18 and 19 from the legs 3 and 4 or from the carriage 15. The shaft, carriage and links 18 and 19 may then be removed as a unit from the head 1.

In connection with the embodiment shown in Figures 5, 6 and 7 the use may be described as follows: Assuming that its points are in closed relation as shown in a portion of Figure 5 and it is desired to separate them in spaced parallel relation such as is illustrated by another portion of Figure 5 the user loosens the nut 39 and rotates the nut 29 and the shaft 27 to which it is secured. According to the direction of rotation of the nut 29 the carriage 32 may be caused to travel axially up or down the shaft 27 to separate

or bring the parts in closed positions as illustrated in the lower portion of this figure. When the desired adjustment is obtained, the nut 39 is tightened on the shaft 27 to 5 maintain this adjustment.

It will be seen that I have provided a very simple instrument for accurately and quickly adjusting a compass or divider or other geometrical instrument of like nature in such 10 a manner that the operating points may be maintained in substantially parallel planes throughout any adjustment thereof. At the same time I have provided a sturdy structure which is extremely simple and inexpensive 15 to manufacture. Furthermore this device may be readily disassembled for repair or cleaning and may be reassembled again without in any way impairing the usefulness thereof.

20 Various changes in the details of construction and arrangement of parts may be made without departing from the spirit of my invention or the scope of the appended claim.

I claim:

25 A device of the class described including a head, legs pivoted to the head, elongated instrument carrying extensions pivotally carried by the legs, means for maintaining the extensions substantially parallel 30 throughout the movement of said legs, and means for moving the legs to a predetermined adjusted position, said last named means including a stem operable in the head and threaded throughout its major portion, 35 a carriage threadedly engaging the threads of the stem and movable along the stem, and links pivotally connecting the carriage with the said respective legs, and a set screw carried by the said head and engageable with the 40 stem to lock the same in predetermined adjustment in the head.

In testimony whereof, I hereunto affix my signature.

ADOLPH A. VLCEK.
